UNITED STATES PATENT OFFICE.

HARRY A. LEWIS, OF NORRISTOWN, PENNSYLVANIA.

METHOD OF ROLLING METAL.

1,370,694.

Specification of Letters Patent.

Patented Mar. 8, 1921.

Application filed October 23, 1919. Serial No. 332,608.

To all whom it may concern:

Be it known that I, HARRY A. LEWIS, a citizen of the United States, and resident of Norristown, in the county of Montgomery and State of Pennsylvania, have invented a new and useful Improvement in Methods of Rolling Metal; and I do hereby declare the following to be a full, clear, and exact description thereof.

10 My invention relates to methods of rolling metal.

One object of my invention is to provide for the simple feeding of metal which requires to be reversed or turned during reduction, for example, in connection with the rolling of plates or sheets.

Another object of my invention is to provide for the effective removal of scale from the metal during the rolling operation, this 20 result being accomplished by turning the metal over between successive reductions and thereby bending the metal alternately in opposite directions.

To these ends, the invention consists in 25 delivering the blank from the reducing or operating rolls into a holder and while the blank is contained in that holder turning the blank, for example, by means of turning the holder, and then feeding the blank from 30 the holder over the top roll of the reducing rolls, or into a pass in the reducing rolls at another level than the pass which delivered the blank into the holder. The particular method will be fully set forth and claimed.

35 In the drawings, Figure 1 is a plan view of apparatus adapted for the practice of the invention; Fig. 2 is a longitudinal section of said apparatus on line 2—2, Fig. 1; Fig. 3 is a cross section on the line 3—3, 40 Fig. 1; and Fig. 4 shows the invention applied to a three-high mill.

In order that the invention may be clearly understood, I will describe the same in connection with the rolling of plates or sheets 45 as practised in connection with both a two-high and a three-high mill, though it is to be understood that the invention is applicable to any method, such as described and claimed.

50 In the drawing, the numeral 2 designates suitable housings of a two-high mill in which the rolls 3 are mounted in the ordinary manner, and adapted to be driven in opposite directions, by suitable mechanism, 55 as shown by the arrows on Fig. 2. My in-

vention can be employed in connection with any suitable holder adapted to the practice of the particular steps involved and I will describe apparatus suitable for that practice in a simple form in connection with the 60 manufacture of sheet or plate metal. In front of the rolls is an ordinary roller table provided with the feed rollers 5, said feed rollers being driven in any suitable way, such as by bevel gears 6, which are engaged 65 by bevel gears 7 on the outer driven shaft 8. In this manner the feed rollers in ordinary operation are driven in the direction of the arrows on Fig. 2, so that the metal deposited thereon is fed through the pass 70 between the reducing rolls 3. On the opposite side of the rolls is mounted a suitable holder into which the metal plate, which is shown in dotted lines, is deposited, and which illustrates one well adapted form of 75 return feed mechanism.

This holder is in the form of a cage 14 supported on two curved guides 10 and 12, carrying the grooved anti-friction rollers 11 and 13, respectively, and the cage 14 has 80 the annular flanges 15 and 16 which engage with the grooved rollers 11 and 13 and thus support the cage. A circular rack 22 is formed on the feeding member or cage 14 which engages with the pinion 23 mounted 85 on the shaft 24, which shaft is driven by any suitable mechanism for the turning of the cage, as desired. The cage, as thus mounted has its axis of rotation at right angles to the rolls, and at a higher level than the center of the top reducing roll. This cage as 90 illustrated, has two inclined guide-ways 25 and 26, which as illustrated are formed of sets of idle rollers 18 and 19, so spaced apart as to form the guideways, and the idle rollers of each set may be arranged for adjustment toward and from each other in any desired way, in order to provide for handling sheets and plates of different thicknesses. The cage has also stop plates 20 which close 100 the outer ends of the guide-ways and prevent the sheets from passing out at the outer end of the cage.

A suitable guide 21 is provided to direct the sheet between the rollers 18 or 19, according to which set is in the lowermost position. Side guides 30 may also be provided for preventing the material from slipping out of the cage while the cage is being revolved. These guides may be ar- 110

ranged for adjustment in any desired way to accommodate sheets or plates of different widths.

When the invention is practised with the above form of apparatus in the rolling of plates or sheets in a two-high mill, a suitably heated blank is placed upon the feed rollers 5 and fed thereby through the reducing rolls 3 and is delivered therefrom 10 into a guide-way, say the guide-way 25 of the cage or holder 14, and as such guide-way is downwardly inclined in the position illustrated, the blank drops down upon the outer roller table or set of rolls 18 and rests 15 thereon. By the rotation of the cage, this blank is then raised upwardly and given a half turn so that it drops down upon the lower or inner set of rolls 19 and is held by the same in a position inclined downwardly 20 toward the reducing rolls. It then by its own weight passes downwardly from the cage, for example, over the guide roll 29 in the housing and over the top roll of the reducing rolls 3, and drops down upon the 25 feed rollers of the table 5, which are revolving toward the reducing rolls 3, and the blank is thereby fed forward into the reducing rolls, and through the same and into the inclined guide-way 26 which by 30 the above operation, has been moved from above into receiving position and receives the blank. While the blank is held in the guide-way, the rack is again turned, bringing that guide-way into upper position, and 35 feeding the blank in the course above described. Thus, without handling, the blank is quickly fed in the course proper for its turning and reduction, and it can be reduced at greater speed and without manual labor 40 so that a larger and consequently a more rapid reduction can be obtained and danger to the workmen entirely avoided. When the blank has been reduced to finished sheet or plate form, it can be removed from the 45 mill by the reversal of the feed table 5 or any other desired way.

The cage 14 may be given its step-by-step rotation always in the same direction, or it may, if desired, be oscillated, first in one 50 direction, and then in the other. As a further modification, more than two sets of the blank-holding guides 18-19 may be provided, the guides or holders in every case being equally spaced around the periphery of the cage 14, and the step-by-step rotation of the cage 14 being so adjusted that each step brings the next empty holder 55 into position to receive a sheet and brings the next full holder into position to discharge its sheet.

When the invention is applied to a three-high mill, it can be employed as illustrated in Fig. 4, suitable pinch feed rollers 30 being provided as illustrated, and these

pinch rollers may be power driven by suitable mechanism, if desired.

The blank can thus be received from the upper guideway and positively fed into the upper pass of the three-high mill. The apparatus may be varied as desired, and according to the character of the metal operated upon.

It is characteristic of the method of my present invention that the blanks are inverted laterally as distinguished from being turned end for end. This is to say, each blank after passing through the rolls is inverted by being tilted or revolved around an axis perpendicular to the rolls so that, although the blank is repeatedly turned over, 80 the front and rear edges of the blank always remain in the same relative positions.

It is to be understood that my method is not restricted to the use of the particular apparatus which I have shown and described, or to the treatment of any particular material, and I therefore desire that no limitations be placed upon my invention except such as are indicated in the appended claims.

What I claim is:

1. The method of rolling metal that comprises delivering a blank from reducing rolls into a holder, turning the blank laterally while it is contained in the holder 95 and then feeding the blank from the holder over the top roll of the reducing rolls.

2. The method of rolling metal that comprises delivering a blank from reducing rolls into a holder, supporting the blank 100 therein on a downward incline, turning the blank while in said holder to raise it to an upward incline with respect to the rolls and then feeding the blank from the holder over the top roll of the reducing rolls.

3. The method of rolling metal that comprises delivering a blank from reducing rolls into a holder, supporting the blank 110 therein on a downward incline, turning the blank while in said holder to raise it to an upward incline with respect to the rolls, and then feeding the blank by gravity from the holder over the top roll of the reducing rolls.

4. The method of rolling metal that comprises delivering a blank from reducing rolls to a holder, and while the blank is held by said holder inverting the blank laterally and feeding it into another roll pass 115 of the mill at another level than that at 120 which it was received by the holder.

5. The method of rolling metal that comprises delivering a blank from reducing rolls to a rotary holder, imparting to said holder a rotary movement across the direction of travel of the blank, and removing the blank from the holder.

6. The method of rolling metal that com-

prises delivering a blank from reducing rolls to a rotary holder, inverting the blank by rotating said holder across the direction of the travel of the blank, and removing 5 the blank from the holder.

7. The method of rolling metal that comprises delivering a blank from reducing rolls to a holder, moving said holder to invert said blank laterally, removing said 10 blank from said holder, and returning it to the entry side of the reducing rolls, and again feeding the blank to the reducing rolls.

8. The method of rolling metal that comprises delivering a blank from reducing rolls to a holder, mechanically moving said holder to invert said blank laterally, mechanically removing said blank from said holder and returning it to the entry side of 15 the reducing rolls and again feeding the blank mechanically to the reducing rolls.

9. The method of rolling metal that comprises delivering a blank from one pass of a set of reducing rolls to a holder, automatically moving said holder to invert said blank laterally, mechanically removing said 20 25

blank from said holder and returning it through another pass of said set of rolls to the entry side of the reducing rolls, and again feeding the said blank mechanically 30 to said reducing rolls.

10. The work-holding method that comprises delivering a flat article to a holder, moving said holder to rotate the plane of said article laterally with respect to the direction in which said article is delivered to 35 said holder, and removing said article from said holder.

11. The work-holding method that comprises delivering an article to a holder, automatically moving said holder to invert said article laterally with respect to the direction in which said article is delivered to said holder, and removing said article from 40 45 said holder.

In testimony whereof, I, the said HARRY A. LEWIS, have hereunto set my hand.

HARRY A. LEWIS.
